DESIGN FOR A BUILDING SIDING

Robert S. Maclean, South Bend, Ind., assignor to
Mastic Asphalt Corporation, South Bend, Ind.,
a corporation of Indiana

Application August 17, 1936, Serial No. 64,439

Term of patent 14 years

To all whom it may concern:

Be it known that I, Robert S. Maclean, a citizen of the United States, residing at South Bend, in the county of St. Joseph, State of Indiana, have invented a new, original, and ornamental Design for a Building Siding, of which the following is a specification, reference being had to the accompanying drawing, forming a part thereof.

Fig. 1 is a view in side elevation of a part of

a building siding composed of assembled members of my new design; and

Fig. 2 is a perspective view of one of the units used to form the building siding shown in Fig. 1.

I claim:—

The ornamental design for a building siding substantially as shown.

ROBERT S. MACLEAN.
